UNITED STATES PATENT OFFICE.

TALBOT G. MARTIN, OF CHICAGO, ILLINOIS, ASSIGNOR, BY WRITTEN ASSIGNMENTS, TO FIRST TRUST AND SAVINGS BANK, TRUSTEE, OF CHICAGO, ILLINOIS.

TRUNKING ARRANGEMENT FOR AUTOMATIC TELEPHONE EXCHANGES.

1,177,789.

Specification of Letters Patent

Patented Apr. 3, 1916.

Application filed July 23, 1906. Serial No. 327,352.

To all whom it may concern:

Be it known that I, TALBOT G. MARTIN, a citizen of the United States of America, and resident of Chicago, Cook county, Illinois, have invented a certain new and useful Improvement in Trunking Arrangement for Automatic Telephone Exchanges, of which the following is a specification.

My invention relates to telephone systems in general, but more especially to automatic or semi-automatic telephone exchange systems, and particularly to automatic trunking between different exchanges or central stations.

Generally stated the object of my invention is the provision of an improved and highly efficient telephone exchange system.

Special objects are the provision of an improved arrangement for automatically trunking between different exchanges or central stations; the provision of improved means whereby the calling subscriber may employ one or more relays for successively controlling a plurality of automatic switches, such, for example, as a second-selector and a connector; the provision of a repeater having a pair of crossed line conductors, and having a pair of inductive relay coils through which current for talking purposes is supplied to the calling subscriber's line, and by which the calling subscriber controls a selector or connector or other switching machine over a trunk line leading thereto and formed by a continuation of the said crossed conductors; the provision of a common battery telephone system having means for insuring against uncertainty of action on the part of a selector or connector, or any other switching machine, which it may be found necessary for a calling subscriber to control through the medium of a repeater having condensers or other inductive devices or connections which might, during the transmission of impulses over the calling line, tend to produce (by static discharges) confusion or uncertainty of operation on the part of said selector or connector, or other suitable switching machine; and the provision of certain details and features of improvement and novel combinations tending to increase the general efficiency and serviceability of a telephone exchange system of this particular character.

It will thus be seen that my invention is in the nature of an improvement upon my

co-pending application Serial No. 262,728, filed May 23, 1907.

To the foregoing and other useful ends, my invention consists in matters hereinafter set forth and claimed.

In the accompanying drawings, Figure 1 is a diagram showing a subscriber's line connecting the sub-station A (#5000) with its allotted first-selector B and the repeater C. Fig. 2 shows in diagram a called substation D (#2220), a first-selector E allotted to the called line, the connector F and a second-selector G. Fig. 1 represents the apparatus of one exchange, which will be designated as central office #1, and Fig. 2 represents the apparatus of the second exchange, which will be designated as central office #2; and Figs. 1 and 2 taken together represent an established connection between the subscribers A and D, involving the principles of my invention. Fig. 3 shows another method of crossing the line conductors in the repeater.

Each central office has its own battery, the central office #1 having its battery B¹ with its positive terminal preferably grounded at G¹, and the central office #2 having its battery B² with its positive terminal preferably grounded at G². These batteries may be of any suitable voltage, but good results are obtained when they are built to give a pressure from 10 to 30 volts.

The substation may be of any suitable or approved type. The substation shown in Fig. 1 is provided with the usual receiver 2, transmitter 3, induction coil 4, condenser 5 and the switch hook 6, together with the signaling device 7 and a calling device represented as having two push buttons 8 and 9 in connection with a number of springs, and other essential details of construction. The ringer 10 is normally connected across the line, which connection is controlled by the switch hook 6. In making a call the subscriber alternately grounds the metallic lines the proper number of times, and to release—that is, to restore the switching apparatus after it has been operated—the subscriber by restoring his receiver grounds both sides of the line simultaneously for a moment.

The first-selector may be of any suitable or approved type, such as the selector described in Patent No. 815,821, granted March 13, 1906, to Fleith, Erickson & Erickson.

The subscriber's vertical and rotary line conductors 11 and 12, respectively, terminate in the vertical and rotary line relays 13 and 14, the connection being maintained through the side switch wipers 15 and 16. The former wiper is normally in engagement with the contact point 17 and the latter with the contact point 18. The side switch is well known, and comprises besides the side switch wipers 15 and 16 the private side switch wiper 19 and the rotary magnet side switch wiper 20. The side switch is controlled by the private magnet 21, and in the normal or first position of the side switch the side switch wipers 15, 16, 19 and 20 engage the contact points 17, 18, 22 and 23, respectively. In second position they rest on the contact points 24, 25, 26 and 27. In third position they engage the contact points 28, 29, 30 and 31, respectively. Through the medium of the vertical line relay 13, and while the side switch is in first position, the subscriber controls the vertical magnet 32 which operates vertically the switch-shaft (not shown) that carries the line wipers 33 and 34 and the private wiper 35. Through the medium of the rotary line relay 14, and while the side switch is in first or second position, the subscriber controls the private magnet 21 and, therefore, the side switch. When the side switch is in second position the rotary magnet 36 is energized and the switch-shaft that carries the wipers 33, 34 and 35 is operated in a rotary direction. The vertical and rotary line relays 13 and 14 provide the means by which the release magnet 37 is controlled by the subscriber while the side switch is in first or second position. If the side switch passes to third position, however, since the selector B is of the trunk release type, the selector is controlled through the next switch with which a connection has been established, and through the private wiper 35 by means of the back-release-relay 35'. The switch-shaft of the selector B carries a so-called normal post arm 38 which, when the shaft is in normal position, presses the spring 39 into engagement with the contact point 40, and thereby maintains a connection between the bridge-cut-off-relay 41 and the private normal conductor 42 that leads to the connector private bank. By way of the said private normal conductor, furthermore, the bridge-cut-off-relay 41 is energized whenever any subscriber calls the substation A. The bridge-cut-off-relay controls a connection between the vertical and rotary line relays 13 and 14 and between the said relays and battery B¹. It is desirable to disconnect the relays from each other and from the battery because if not the ringing current for signaling the substation A may operate either or both of the relays 13 and 14 and cause some interference with the connection. It is also de-

sirable, as is well known, to remove the bridge formed through the said line relays 14 and 13 from across the line to give the voice-currents as clear a path as possible. Whenever the selector-switch B is operated, however, the spring 39 engages the ground contact 43 just above it and thus grounds the private normal conductor 42 and the private bank contacts at the connector banks corresponding to the number of the substation A, so that no calling subscriber may be able to call in upon substation A's line after a calling operation has once been started from that station.

The repeater C of my invention has no movable parts such as the shaft and side switch in the selector, but is made up of a number of relays and springs and other details as follows: The instrument is designed to be bridged permanently across a trunk line, or other line, in the same manner as the repeater C is shown bridged across a trunk line that connects the exchange #1 with exchange #2. The said repeater is provided with a vertical line relay 44, a rotary line relay 45, a differential relay 46, a pole changing relay 47, a resistance-coil 48 and a couple of condensers 49 and 50. The line relays 44 and 45 control between them the trunk release springs 51 and 52 and the line relay springs 53 and 54, the latter two with respect to the ground spring 55. The pole changing relay has allotted to its control the springs 56, 57, 58, 59, 60 and 61. After connection has been established between the substation A and the repeater C the impulses delivered to the vertical line conductor 11 are received by the vertical line relay 44 and repeated to the vertical trunk conductor 62. Under similar conditions, however, impulses delivered from the substation A to the rotary line conductor 12 are received by the rotary line relay 45 and repeated to the rotary trunk conductor 63. The differential relay 46 is provided with two windings 64 and 65 which are so wound that if current is sent through them when they are connected in series with the subscriber's line conductors 11 and 12, the relay 46 will not magnetize. The office of this relay is to provide means whereby the calling subscriber may be able to release after a called subscriber has answered. Furthermore, the differential relay, being provided with the spring 66 and contact point 67, prevents impulses that are repeated from the subscriber's line conductor 11 to the vertical trunk conductor 62 from passing to the rotary trunk conductor 63; and it also prevents impulses repeated from the subscriber's rotary line conductor 12 to the rotary trunk conductor 63 from passing to the vertical trunk conductor 62.

The second-selector G is the same as the first-selector B with the exception that there

are no normal conductors like the normal conductors 68 and 69 leading to the connector banks. There is also no use in the second-selector for such a relay as the 5 bridge-cut-off-relay 41 of the first-selector B and it is, therefore, omitted. The vertical and rotary line relays 70 and 71 are therefore connected directly to battery B². There is also no necessity for a private normal 10 conductor such as the private normal conductor 42, and the spring 72 controlled by the normal post arm 73 is connected through an off-normal lamp 74, which latter becomes lighted when the said spring 72 engages the 15 grounded contact point 75, thus indicating to the switchboard attendant when the selector is off normal. Since like parts are likewise represented throughout the drawings, the vertical magnet 76, the release-magnet 77, rotary magnet 78, private magnet 79 and the back-release-relay 80 will be 20 recognized and understood.

The connector-switch F may also be of any suitable or approved type, for instance 25 of the general type described in Patent No. 815,176, granted March 13, 1906, to Keith, Erickson & Erickson. The mechanical details of the selector and connector, as is well known, are very much the same, although 30 there is some material difference in the circuits. For instance, the connector switch shaft, which is not shown, carries, like the selectors, the line wipers 81 and 82 and the private wiper 83. The connector switch is 35 also controlled by the calling subscriber through the medium of the vertical and rotary line relays 84 and 85. The vertical line relay 84 directly controls the vertical magnet 86 and also the rotary magnet 87. The 40 office of the said magnet 86 is to give the shaft and shaft wipers their vertical movements, and the rotary magnet 87 imparts to the said shaft and wipers a rotary or circular movement. The rotary line relay 85 45 controls the private magnet 88, which latter under certain conditions controls in turn the vertical and rotary magnets 86 and 87, the release-magnet 89 and also the side switch wipers 90, 91, 92 and 93. The said side 50 switch, like the side switch of the selector, has a normal or first position, a second and a third position. In the normal position the respective side switch wipers 90, 91, 92 and 93 engage the contact points 94, 95, 96 and 97; in second position the wipers engage 55 the contact points 98, 99, 100 and 101; and in third position they engage the contact points 102, 103, 104 and 105. The release-magnet 89 is also controlled by the line 60 relays 84 and 85 conjointly, and by the circuit controlling relay 106. Like the repeater the connector divides the circuit that passes through it into two sections by the use of the condensers 108 and 109. The connector 65 has in addition a ringer relay 110 by means

of which the ringer generator 111 is bridged across the terminals of the called line to signal the called subscriber. Each exchange has a busy signaling apparatus H of any suitable design, as for example the one comprising 70 an interrupter 112 in series with a primary winding 113 of an induction-coil 114 whereby a busy signaling current is induced into the secondary winding of the said induction-coil 114. The secondary 75 winding 115 is connected to the contact point 116 against which the switch shaft spring 117 is allowed to press when the normal post arm 118 rises.

The first-selector E of the called line is 80 the same as the first-selector B and needs, therefore, no description. The substation D is, of course, also the same as the substation A.

The connection between the two exchanges 85 may be arranged in any convenient manner, and I do not confine myself to any particular arrangement, since the system herein disclosed admits of an indefinite number of arrangements. If it is assumed 90 that the maximum number of subscribers to be accommodated at each of the exchanges #1 and #2 is five thousand, then the first five levels of the first-selectors of exchange #1 may be devoted to local connections and the last five levels to trunk connections for exchange #2; each of which trunk connections, of course, comprises a repeater similar to the repeater C. At the exchange #2 a similar arrangement may 95 prevail, but with the exception that the first five levels would be devoted to trunking apparatus at the exchange #1 and the last five levels to local connections. However, any suitable arrangement may be resorted 100 to. It will be understood that the switches may be arranged in groups; for example, the first-selectors may be arranged in groups of one hundred having all similar bank contacts connected in multiple. Therefore, there will be one hundred line terminals in multiple with each trunk line, and corresponding to each trunk line there will be one hundred private bank contacts in 105 multiple.

The operation in detail is as follows: To 110 call the number 2220 the subscriber at substation A operates his calling device in a suitable manner corresponding to each digit. For each digit the vertical line is 115 grounded a certain number of times corresponding to the numerical value of the digit, and then the rotary side of the line is grounded once. The first digit being 2 the subscriber at substation A removes his receiver 2 from the switch-hook 6, which latter then causes the ground springs 119 and 120 to close contact, the secondary circuit springs 121 and 122 close contact, the springs 123 and 124 close contact, and the 125

switchhook breaks connection with the spring 125, and the calling subscriber then proceeds to press the button 8 twice corresponding to the value of the digit. The engagement of the ground springs 119 and 120 places the ground post 126 in connection with the substation ground G^3 . Therefore, each time that the button 8 is pressed the spring 127 leaves the contact point 128 and is grounded on the ground post 126, and as a result the vertical line relay 13 of the selector B is energized once. The current for energizing said relay 13 flows from ground G^3 through the ground springs 119 and 120 to the ground post 126, thence to the vertical line conductor 11, side switch wiper 15, contact point 17, vertical line relay 13, bridge-cut-off-relay springs 129 and 130 to the battery lead 131, thence through battery B^1 to ground G^1 . Each time that the vertical line relay 13 is energized the line relay springs 132 and 133 are pressed into contact and an energizing circuit is thereby established each time through the vertical magnet 32. Current for said magnet flows from ground G^4 through the springs 133 and 132, private springs 134 and 135, vertical magnet 32 to the battery lead 131, thence through battery B^1 to ground G^1 . The vertical magnet 32 then operates to raise the shaft two steps, thus placing the wipers 33, 34 and 35 on a level with the contact points that constitute the terminals of the trunk line leading to the repeater C. The subscriber then presses the rotary button 9, causing the spring 136 to leave the contact point 137 and to be grounded on the ground post 126. As a result the rotary line conductor 12 is grounded and the rotary line relay 14 is in turn energized. The current through the said relay 14 flows from ground G^3 to the ground post 126, thence over the rotary line conductor 12 to the side switch wiper 16, contact point 18, rotary line relay 14, bridge-cut-off-relay springs 138, 129 and 130, thence through battery B^1 to ground G^1 . The rotary line relay 14 in turn energizes the private magnet 21 by closing connection between the springs 133 and 139. The current for energizing the private magnet flows from ground G^4 through the springs 133 and 139 to the private magnet 21, and through battery B^1 to ground G^1 . The private magnet 21 then operates to release the side switch from first to second position, and as a result a circuit is closed through the rotary magnet 36 when the side switch wiper 20 engages the contact point 27. The current through the rotary magnet flows from ground G^5 to the contact point 27, thence through the side switch wiper 20, rotary magnet 36, rotary magnet interrupter springs, to the battery lead 131 and through battery B^1 to ground G^1 . The rotary mag-

net is energized one step and the wipers 33, 34 and 35 carried into engagement with the bank contacts that constitute the terminals of trunk lines. If the first trunk line is busy an energizing circuit is established through the private magnet 21 when the private wiper 35 strikes a grounded contact. The current flows, in that case, from ground to the private wiper 35, thence through the back-release-relay 35', side switch wiper 19, contact point 26, private magnet 21 to the battery lead 131, thence through battery B^1 to ground G^1 . As long as the private wiper 35 passes over the busy contact point the private magnet 21 is retained energized and the side switch is locked in second position, as is well known, until the rotary magnet, by energizing step by step, carries the wipers past the last busy trunk line. However, as soon as the private magnet deenergizes, the side switch is tripped into third position, or if there are no busy contacts to be passed over, the rotary magnet 36, as is well known, trips the side switch to third position with the result that as soon as the side switch wipers 15 and 16 engage the respective contact points 28 and 29 the subscriber's line conductors 11 and 12 are extended to the repeater C. Also, since the side switch wiper 19 at the same time engages the grounded contact point 30, a guarding potential is established at the private wiper 35 for protecting the seized trunk line to the repeater C from being molested by any other switch. The second digit being 2 the calling subscriber presses the button 8 twice and grounds the vertical line conductor 11 twice. Grounding the vertical line conductor twice energizes the vertical line relay 44 twice. The energizing current in each case flows from ground G^3 at the substation to the ground post 126, thence through the spring 127 to the vertical line conductor 11, side switch wiper 15, contact point 28, vertical line wiper 33, vertical line relay 44 of the repeater C, winding 64 of the differential relay 46, pole changing relay springs 66 and 61 to the battery lead 131, thence through battery B^1 to ground G^1 . Since the current flows not only through the vertical line relay 44 but also through the winding 64 of the differential relay 46, the said differential relay energizes simultaneously with the said vertical line relay. Each time that the vertical line relay is energized the springs 53 and 55 are pressed into contact, each time grounding the vertical trunk conductor 62 over the following circuit: from ground G^6 through the pole changing relay springs 59 and 58, conductor 140, springs 55 and 53, conductor 141, pole changing relay springs 57 and 56 to the vertical trunk conductor 62. The effect of grounding this vertical trunk conductor 62 will be explained hereinafter. When the differential relay 46 becomes en-

ergized, as stated, at the same time that the vertical line relay 44 is energized, the springs 66 and 67 are separated and the connection between the rotary trunk conductor 63 and the vertical trunk conductor 62 is broken, which is normally closed as follows: from the vertical trunk conductor 62 to the pole changing relay 41, springs 66 and 67 to the rotary trunk conductor 63. In this way the rotary trunk conductor 63 is prevented from being grounded through the pole changing relay 41 each time that the vertical trunk conductor 62 is grounded. After pressing the vertical button 8 twice the subscriber presses the rotary button 9 once and as a result grounds the rotary line conductor 12, and the result is that the rotary line relay 45 and the differential relay 46 are energized together. The energizing current flows from ground G^2 to the ground post 126, thence through the spring 136 to the rotary line conductor 12, thence to the side switch wiper 16 of the selector B, contact point 29, shaft wiper 34, rotary line relay 45, winding 65 of the differential relay 46 to the battery lead 131, thence through battery B^1 to ground G^1 .

Each time that the rotary line relay 45 energizes, the springs 55 and 54 are pressed into contact and as a result the rotary trunk conductor 63 is grounded. The differential relay operating at the same time separates the springs 66 and 67 and prevents the grounding of the vertical trunk conductor 62 in a manner previously described. A circuit over which the vertical trunk conductor 63 is grounded is as follows: from ground G^1 through the spring 55 and 54 to the conductor 140, thence to the ground spring 55, rotary line relay spring 51, conductor 142 to the rotary trunk conductor 63. The effect of grounding the rotary trunk conductor 63 will presently be considered. First it will be well to consider the effect of grounding the vertical trunk conductor 62 as a result of the subscriber's operation corresponding to the second digit. The said trunk conductor 62 being normally connected with the vertical line relay 70 of the second-selector G, each time that the said conductor is grounded the said relay 70 is operated. The flow of current may be traced from ground G^1 at the repeater C (Fig. 1) to the vertical trunk conductor 62, thence to the side switch wiper 143 of the second-selector G (Fig. 2), contact point 144 to the vertical line relay 70, thence through the said relay to the battery lead 145, thence through the battery B^1 to ground G^1 . The vertical line relay 70 in turn operates the vertical magnet 76 as described in the selector B (Fig. 1) so that the shaft wipers 146, 147 and 148 are raised to a level with the centers of the trunk line that leads to the connector F. The energizing circuit

through the said vertical magnet 76 is established when the springs 149 and 150 are pressed into contact, and extends from ground G^1 through the springs 150 and 149 through the private springs 151 and 152 to 70 the vertical magnet 76, thence to the battery lead 145 and through battery B^2 to ground G^2 . As soon as the switch-shaft is raised the normal post arm 73 permits the switch-shaft spring 72 to engage the grounded contact 75 and the off-normal lamp 74 flashes up to indicate that the said switch is in use. Returning now to the grounding of the rotary trunk conductor 63, since the said conductor is normally connected to the side 80 switch wiper 153 and with the contact point 154, the rotary line relay 71 is energized. The current flows from ground G^2 at the repeater C (Fig. 1) to the rotary trunk conductor 63, thence to the side switch wiper 153 of the selector G (Fig. 2) to the contact point 154, rotary line relay 71 and through the said relay to the battery lead 145 and through battery B^2 to ground G^2 . The rotary line relay upon energizing in turn 85 energizes the private magnet 79 momentarily, which latter in turn permits the side switch to escape to second position. As soon as the side switch wiper 155 engages the contact point 156 an energizing circuit is 95 established through the rotary magnet 78, which latter then operates to rotate the shaft in the manner described in connection with the first-selector B. The current through the said rotary magnet 78 flows from ground 100 G^2 to the contact point 156, thence through the side switch wiper 155, rotary magnet 78, interrupter springs 157 to the battery lead 145, thence through battery B^2 to ground G^2 . When the rotary magnet operates, the side switch is tripped into third position, or if the wipers are carried over busy contacts the side switch does not pass to third position until the private magnet 79 deenergizes after the private wiper 148 110 leaves the last busy contact. As soon as the side switch passes to third position the side switch wipers 143 and 153 upon engaging the contact points 158 and 159, respectively, extend the trunk line conductors 62 and 63 115 to the connector F, and at the same time the side switch wiper 160 engages the contact point 161 and a guarding potential is established at the private wiper 148 for preventing other switches from establishing connection with the connector F. The third digit of the called number being 2 the calling subscriber again presses the vertical button 8 (Fig. 1) twice so that the vertical line conductor 11 is grounded twice. The 120 trunk conductors 62 and 63 being now connected with the connector F, the operation of the subscriber at substation A is directed to the connector F.

Each time that the vertical line conductor 125

11 is grounded the vertical line relay 44 of the repeater C is energized, as well as the differential relay 46, over a well-known circuit. The vertical line relay 44 in turn 5 grounds the vertical trunk conductor 62 twice, and as a result the vertical line relay 84 of the connector F together with the differential relay 162 are energized. The said differential relay is provided with a couple 10 of windings 163 and 164. The circuit for energizing said relays 84 and 162 extends from ground G^a at the repeater C (Fig. 1) to the vertical trunk conductor 62, thence to the side switch wiper 143 of the second- 15 selector G (Fig. 2), contact point 158, vertical line wiper 146, vertical line relay 84, winding 163 of the differential relay 162, through the pole changing relay springs 165 and 166 to the battery lead 145, thence 20 through battery B^2 to ground G^2 . The vertical line relay 84 in turn presses the line relay springs 167 and 168 into contact and as a result the vertical magnet 86 is operated. The current through the said vertical 25 magnet flows from ground G^a through the springs 168 and 167, private springs 169 and 170, side switch wiper 93, contact point 97 to the vertical magnet 86, thence through said magnet and through the circuit-controlling relay springs 171, 172 and 173 to the battery lead 145, thence through battery B^2 to ground G^2 . The vertical magnet 86, as usual, operates to raise the switch-shaft and the wipers 81, 82 and 83. The vertical 30 magnet being operated twice the connector-shaft is raised two steps and the said wipers 81, 82 and 83 are carried to a level in which the line terminal of the subscriber #2220 is located. The energization of the differential relay 162 has no significance at this 35 time. After operating the vertical button 8 with the above result the subscriber then presses the rotary button 9 once, grounds the rotary line conductor 12, and as a result 40 operates the rotary line relay 45 of the repeater C (Fig. 1), together with the differential relay 46. As a result the rotary trunk conductor 63 is grounded once and the rotary line relay 85 of the conductor 45 F and differential relay 162 are energized. The current through said relays 85 and 162 flows from ground G^a at the repeater C (Fig. 1) to the rotary trunk conductor 63, thence to the side switch wiper 153 of the 50 second-selector G (Fig. 2) to the contact point 159 and rotary line wiper 147 to the rotary line relay 85, thence through said relay and through the winding 164 of the differential relay 162 to the battery lead 145 and through battery B^2 to ground G^2 . The rotary line relay 85 upon energizing 55 presses the line relay springs 174 and 168 into contact, establishing, therefore, an energizing circuit through the private magnet 88. The current through said magnet 60 passes from ground G^a through the said springs 168 and 174, thence through the said magnet and through the circuit-controlling relay springs 172 and 173 to the battery lead 145, thence through battery B^2 to ground G^2 . The private magnet being energized for a moment the side switch of the connector passes to second position, permitting the side switch wiper 93 to engage the contact point 101, thus substituting the rotary magnet 87 for the vertical magnet 86 to the control of the vertical line relay 84. The fourth digit of the called number being 0 the subscriber presses the vertical button 8 ten times, as a result grounding the 65 vertical conductor 11 ten times and operating the vertical line relay 44 and the differential relay 46 of the repeater C ten times. The said line relay 44 in turn grounds the vertical trunk conductor 62 ten times, as a result causing the operation of the vertical line relay 84 of the connector F ten times. The current through the said vertical line relay 84 flows through a circuit that has already been described. The vertical 70 line relay in turn presses the line relay springs 167 and 168 into contact, energizing each time the rotary magnet 87. The current flows through said rotary magnet over the following circuit: from ground G^a 75 through the line relay springs 168 and 167 to the side switch wiper 93, thence through the contact point 101, vertical magnet 87 and through the circuit-controlling relay springs 171, 172 and 173 to the battery lead 145, thence through battery B^2 to ground G^2 . The rotary magnet 87 each time it is energized rotates the shaft and shaft wipers 81, 82 and 83 one step at a time until they 80 are carried into engagement with the normal conductors 175, 176 and 157 that lead to the first-selector E of the called line. The former two of said conductors (175 and 176) do not terminate at the first-selector E but continue through to the line conductors 110 177 and 178 of the called substation D. The subscriber again presses the rotary button 9 and grounds the rotary line conductor 12. He then operates the rotary line relay 45 of the repeater C (Fig. 1), grounds the rotary 115 trunk conductor 63 and energizes the rotary line relay 85 (Fig. 2) of the connector F. The energization of the said relay 85 causes either of two results—the release of the side switch from second to third position, if the 120 called line is not busy, or the release of the connector-switch F, if the called line is busy, the former operation placing the side switch wipers 90 and 91 in engagement with the contact points 102 and 103, thus connecting the calling subscriber's line with the 125 called subscriber's line. The circuit over which the two substations are connected, if the side switch passes to third position, is marked by the heavy lines in Figs. 1 and 2. 130

It will be well to consider first the former of said results, namely the release of the side switch from second to third position. The rotary line relay 85, when it presses the springs 168 and 174 together, energizes the private magnet 88 over a circuit previously described. The said private magnet operating momentarily releases the side switch from second to third position. As a result the side switch wipers 90 and 91 engage the contact points 102 and 103 so that the trunk conductors 62 and 63 between the exchanges #1 and #2 are placed in connection with the subscribers' vertical and rotary line conductors 177 and 178, respectively. At the same time the side switch wiper 92 passes onto the grounded contact point 104 and a guarding potential is set up at the private wiper 83 for protecting the called line after connection has been established. The circuit for the establishment of the guarding potential at the said private wiper extends from ground G^{10} to the contact point 104, side switch wiper 92, conductor 179 to the private wiper 83. A guarding potential at the said private wiper 83, furthermore, sends a flow of current through the bridge-cut-off-relay 180 of the first-selector E, whereby the said relay when energized separates the springs 181, 182 and 183, as a result disconnecting the vertical and rotary line relays 184 and 185 from the battery lead 145 and from each other, so as to leave a talking and ringing circuit free. The current through said bridge-cut-off-relay 180 flows from the private wiper 83 to the private normal conductor 157^a, thence through the switch shaft springs 186 and 187 to the bridge-cut-off-relay 180, thence to battery lead 145 and through battery B^2 to ground G^2 . To signal the called subscriber the calling subscriber presses his signaling button 7, pressing the spring 188 away from the contact point 189 and onto the ground contact point 190. The union of said springs 188 and 190 grounds the vertical line conductor 11 over a circuit that extends from ground G^3 through the ground springs 119 and 120 to the spring 190, thence through the spring 188 to the vertical line conductor 11. As a result the vertical line relay 44 of the repeater C operates to ground the vertical trunk conductor 62 and, therefore, the vertical line relay 84 of the connector F is energized. It will be borne in mind that now the side switch is in third position and the side switch wiper 93 of the connector F is in engagement with the contact point 105; therefore when the vertical line relay presses the springs 167 and 168 into contact the ringer relay 110 is energized by a flow of current from ground G^6 to the side switch wiper 93, thence through the ringer relay 110 and through the circuit-controlling relay springs 171, 172 and 173

to the battery lead 145, thence through battery B^2 to ground G^2 . The ringer relay upon energizing shifts the springs 191 and 192 from the springs 193 and 194 and onto the springs 195 and 196. The result is that 70 the calling line is separated from the called line and the ringer generator 111 is bridged across the latter. A signaling current is, therefore, sent from the ringer generator 111 to the subscribers' line conductors 177 and 178, thence through the switch-hook 197 and spring 198 and bell 199 to the rotary line conductor 178. Busy lines may be either 75 calling or called, and the way in which protecting guarding potentials are established 80 has already been explained.

The calling line is protected by a guarding potential established at the connector banks from the calling first-selector, and the called line is protected by a guarding potential established by the connector. In either case if the line is busy, therefore, there is a guarding potential at the private bank contact that corresponds to the called number. The busy release follows as a result 90 of the energization of the rotary line relay for the last digit, if the called line is busy, as follows: The said relay 85 upon energizing energizes the private magnet 88, as already described, which latter in turn presses the 95 springs 200 and 201 into contact. As soon as the said springs 200 and 201 engage the release-magnet 89 is placed in connection with the private wiper 83 (since the side switch wiper 92 is now in second position 100 and in engagement with the contact point 100), which latter has been previously rotated onto a grounded contact. As a result a flow of current is sent through the release-magnet 89 from the grounded private wiper 105 110 83 to the side switch wiper 92, thence through the contact point 100, private springs 201 and 200 to the release-magnet 89, thence through the circuit-controlling relay springs 172 and 173 to the battery lead 145, thence through battery B^2 to ground G^2 . The release-magnet upon energizing releases the connector switch shaft and restores the connector side switch to first position, returning the vertical magnet 86 to 115 the control of the vertical line relay 84. Therefore if the calling subscriber (Fig. 1) presses his signaling button 7 and grounds the vertical line conductor 11 he operates the connector vertical line relay 84, which latter in turn operates the vertical magnet 86. Said vertical magnet raises the switch-shaft so that the normal post arm 118 permits the switch shaft springs 117 and 116 to come into contact and a busy signaling current is sent to the calling subscriber's station. The circuit over which the busy signaling current passes is as follows: from the coil 115 of the busy machine H through 120 the contact points 116 and 117 to the side 125 135 180

switch contact point 95, side switch wiper 91, ringer relay springs 191 and 193, condenser 109, rotary line wiper 147 of the second-selector G, side switch wiper 153, rotary trunk conductor 63, condenser 49 at the repeater C (Fig. 1), vertical line wiper 33 of the first-selector B, contact point 28, side switch wiper 15, vertical line conductor 11, receiver 2, secondary winding 202 of the induction-coil 4, condenser 5 to the rotary line conductor 12, thence through the side switch wiper 16 of the selector B, contact point 29, rotary line wiper 34, condenser 50 of the repeater C, vertical trunk conductor 62, side switch wiper 143 of the second-selector G (Fig. 2), contact point 158, vertical line wiper 146, vertical line relay 84 of the connector F, through the winding 163 of the differential relay 162 to the battery lead 145, and thence again to the coil 115 of the busy machine H. The calling subscriber upon hearing the busy signal will understand that the desired line is busy and will release the switching apparatus by hanging up his receiver. The front release occurs when the calling subscriber restores his receiver 2 to the switch-hook 6 and thereby presses into connection for a moment the release-springs 203, 204 and 205. The engagement of the said release-springs grounds the vertical and rotary line conductors 11 and 12 simultaneously, the circuit from ground G^3 to the vertical line conductor 11 being established through the ground springs 119 and 120 to the ground release-spring 204, thence through the release-spring 203 to the vertical line conductor 11. The circuit to the rotary line conductor 12 extends from ground G^3 to the release-spring 204, thence through the release-spring 205 to the rotary line conductor 12. As a result the vertical and rotary line relays 44 and 45 of the repeater C are energized over the usual circuits simultaneously. Said relays in turn ground the vertical and rotary trunk conductors 62 and 63 simultaneously, the effect of which operation will be considered presently.

50 The line relays 44 and 45 of the repeater also press the release-springs 51 and 52 into contact, closing a release circuit through the back-release-relay 35' of the first-selector B, and through the resistance-coil 48 of the repeater C in series. The current for energizing the back-release-relay 35' flows from ground G^{11} at the first-selector B to the contact-point 30, thence to the side switch wiper 19 and through the back-release-relay 35' to the private wiper 35, thence through the trunk release springs 51 and 52 and through the resistance-coil 48, pole changing relay springs 60 and 61 to the battery lead 131, thence through battery B^1 to ground G^1 . When the back-release-relay 35' energizes, the springs 206 and 207 are then pressed into contact and an energizing circuit is established through the release-magnet 37, current flowing from ground G^{12} through the springs 206 and 207 to the said release-magnet, thence to the battery lead 131 and through battery B^1 to ground G^1 . The release-magnet 37 upon magnetizing attracts its armature and remains in readiness to release the switch as soon as the substation release-springs 203, 204 and 205 separate and break the ground connection to the line conductors 11 and 12. The simultaneous grounding of the vertical and rotary trunk conductors 62 and 63 by the line relays 44 and 45 of the repeater C (Fig. 1) results in the energization of the vertical and rotary line relays 84 and 85, which latter press the trunk release springs 208 and 209 into contact and thereby energize the back-release-relay 80 of the second-selector G in series with the release-magnet 89 of the connector F, the current flowing from ground G^{13} at the second-selector G to the contact point 161, side switch wiper 160, back-release-relay 80, private wiper 148, connector trunk release springs 208 and 209 to the release-magnet 89, thence through the said release-magnet and through the circuit-controlling relay springs 172 and 173 to the battery lead 145, thence through battery B^2 to ground G^2 . The release-magnet 89 of the connector F, as soon as it energizes, restores the switch-shaft of the connector to normal position and the normal post arm 118 separates the switch shaft springs 117 and 116, breaking the busy signaling current circuit. The back-release-relay 80, like the back-release-relay 35' of the first-selector B (Fig. 1), energizes the release-magnet 77, which latter is then put in readiness to restore the said second-selector switch as soon as the subscribers' release-springs 203, 204 and 205 separate. All of these operations result as soon as the subscribers' release-springs 203, 204 and 205 come into contact; and as soon as the switch-hook 6 descends sufficiently to separate the said release-springs, the line relays 44 and 45 of the repeater C deenergize, permitting the trunk release springs 51 and 52 to separate, thus destroying the back release circuit that leads to the selector B and through the back-release-relay 35', at which time the said selector B is fully restored. The deenergization of the rotary line relays 44 and 45 removes the ground connection from the trunk conductors 62 and 63, causing the deenergization of the rotary and vertical line relays 84 and 85 of the connector F. When the said connector relays 84 and 85 deenergize, the trunk release springs 208 and 209 separate and as a result the energizing circuit through the back-release-relay 80 of the second-selector G and through the release-magnet 89 of the 135

connector F is destroyed. The connector is thus left fully restored. The deenergization of the back-release-relay 80 causes the deenergization of the release-magnet 77, the latter causing the restoration of the selector G. The calling subscriber thus restores all the switching apparatus which he originally brought into use. The called subscriber answers when his bell 199 is rung, as previously described, and removes his receiver 210 from his switch-hook 197, thus bridging his secondary circuit that includes the said receiver and the secondary winding 211 of the induction-coil 212 across his line. This bridging circuit is completed as soon as the switch-hook permits the springs 213 and 214 to come into contact. Instantly a flow of current is established through the pole changing relay 107 and circuit-controlling relay 106 of the connector F. The current flows from ground G^{10} at the connector F to the contact point 104, side switch wiper 92, springs 216 and 215 of the differential relay 162, circuit-controlling relay 106, ringer relay springs 194 and 192, side switch wiper 90, contact point 102, vertical line wiper 81, vertical normal conductor 175, vertical line conductor 177, substation springs 214 and 213, springs 217 and 218, transmitter 219, primary winding 220 of the induction-coil 212, rotary line conductor 178, rotary normal conductor 176, contact point 103, side switch wiper 91, ringer relay springs 191 and 193 to the pole changing relay 107, thence to the battery lead 145 and through battery B^2 to ground G^2 . The called subscriber is, therefore, provided with battery for his transmitter as soon as he removes his receiver from his switch-hook. By energizing the pole changing relay 107 the called subscriber causes the spring 165 to leave the spring 166 and to engage the ground spring 221. Current is then sent over the trunk conductors 62 and 63 for energizing the pole changing relay 47 of the repeater C. The circuit over which the said current travels extends from ground G^{14} to the spring 221, thence to the spring 165 to the winding 163 of the differential relay 162, vertical line relay 84 to the vertical trunk conductor 62, thence through the pole changing relay 47 (Fig. 1) of the repeater C, springs 66 and 67 of the differential relay 46 to the rotary trunk conductor 63, thence to the side switch wiper 153 of the second-selector G (Fig. 2), contact point 159, rotary line wiper 147, rotary line relay 85, winding 164 of the differential relay 162 to the battery lead 145, thence through battery B^2 to ground G^2 . When the relay 47 energizes it operates to shift the spring 60 from the spring 61, that is connected with the non-grounded terminal of battery B^1 , to the grounded spring 59. A circuit is thus set up over which current flows through the transmitter 3 of the calling substation A. The path of the current may be traced from ground G^6 through the springs 59 and 60, conductor 222 to the winding 64 of the differential relay 46, thence through said winding through the winding of the vertical line relay 44 to the wiper 33 of the first-selector B, contact point 28, side switch wiper 15, vertical line conductor 11, spring 127, contact point 128, springs 124 and 123, springs 122 and 121, transmitter 3, primary winding 223 of the induction-coil 4, contact point 137, spring 136 to the rotary line conductor 12, thence to the side switch wiper 16 of the first-selector B, contact point 29, wiper 34, rotary line relay 45, winding 65 of the differential relay 46 to the battery lead 131, thence through battery B^1 to ground G^1 . It will be noticed that the energizing circuit for the pole changing relay 47 of the repeater C comprises also the line relays 84 and 85 of the connector F (Fig. 2), and the magnetizing current that flows through said circuit is strong enough to operate said relays 84 and 85; therefore the trunk release springs 208 and 209 are pressed into contact. Ordinarily this would establish an energizing circuit through the release-magnet 89; but since the energizing circuit for the release-magnet comprises the circuit-controlling relay springs 172 and 173, and since the circuit-controlling relay 106 is energized, the said springs 172 and 173 are separated at the time, whereby the energizing circuit through the release-magnet is maintained open after the called subscriber answers and until either the called or calling subscriber hangs up his receiver. It will be noticed also that the line relays 44 and 45 of the repeater C are in the path that provides the transmitter 3 of the substation A with talking current. The said relays 44 and 45 are therefore energized simultaneously, and the trunk release springs 51 and 52 are in contact, but the back-release-relay 35' of the first-selector B is kept short-circuited by the pole changing relay 47 to prevent said relay 35' from releasing the said selector B, and the said pole changing relay 47 being also energized at the time maintains the spring 60 against the ground spring 59, as previously described. The short-circuit is as follows: from ground G^6 of the repeater C through the springs 59 and 60, resistance-coil 48, trunk release springs 52 and 51, trunk release conductor 224, back-release-relay 35', side switch wiper 19, contact point 30 to the ground G^{11} . The subscribers #6000 and #2220 being thus connected and provided with talking current, they converse with each other over the following circuit: Beginning with the transmitter 3 at the substation A it extends through the pri-

mary winding 223 of the induction-coil 4 to the rotary line conductor 12, thence through the side switch wiper 16 of the first-selector B and rotary line wiper 34 to the condenser 50 of the repeater C, vertical trunk conductor 62, side switch wiper 143 of the second-selector G, line wiper 146, condenser 108 of the connector F, ringer relay springs 194 and 192, side switch wiper 90, vertical line wiper 81, vertical line conductor 177, springs 214 and 213 of the substation D, springs 217 and 218, transmitter 219, primary winding 220 to the rotary line conductor 178, thence to the rotary line wiper 82 of the connector F, side switch wiper 91, ringer relay springs 191 and 193, condenser 109, rotary line wiper 147 of the second-selector G, side switch wiper 153, rotary trunk conductor 63, condenser 49 of the repeater C (Fig. 1), vertical line wiper 33 of the first-selector B, side switch wiper 15, vertical line conductor 11 and back to the transmitter 3. The voice-currents in said circuit are induced in the secondary windings 202 and 211 of the induction-coils 4 and 212, respectively, in connection with which coils are the receivers 2 and 210, respectively. The front release after the called subscriber has answered may then be initiated by the calling subscriber in the usual manner—that is, by hanging up his receiver and grounding the vertical and rotary line conductors simultaneously, but the circuits for energizing the release apparatus of the various switches are somewhat different from the circuits over which the front release occurs before the called subscriber answers.

After the called subscriber has answered the subscriber at station A may restore the switches by hanging up his receiver 2 and pressing the release-springs 203, 204 and 205 together, grounding the vertical and rotary line conductors 11 and 12 simultaneously, as already described. Since the pole changing relay 47 is in an energized condition, grounding the vertical line conductor 11 short-circuits the vertical line relay 44 and the winding 64 of the differential relay 46 between ground G^2 and ground G^3 , and as a result the current flowing through said windings 44 and 64 is cut off and the relay 44 is, therefore, deenergized. The winding 65 of the differential relay 46 still maintains its flow of current from ground G^2 to the battery lead 131 and to the battery B^1 ; therefore, the differential relay 46 being thus unbalanced becomes magnetized, separating the spring 66 from the contact point 67, and causing in turn the de-energization of the pole changing relay 47 and of the line relays 84 and 85 of the connector F with which the said pole changing relay 47 is connected in series. As soon as the pole changing relay 47 deenergizes,

however, the spring 58 leaves the spring 57, with which it has been in engagement, and returns to normal engagement with the ground spring 59, so that the ground connection to the ground spring 55 allotted to the line relays 44 and 45 is restored. At the same time the spring 60 returns to normal engagement with the spring 61, so that the vertical line relay 44 becomes reenergized by a flow of current in the opposite direction, which current now flows through the winding 64 of the differential relay 46 in a direction to reinforce the magnetic effect of the winding 65. Both line relays 44 and 45 being now energized simultaneously, the ground connection being re-established to the ground spring 55, and the short-circuit being removed from the back-release-relay 35' of the first-selector B, the following results occur. The simultaneous grounding of the trunk line conductors 62 and 63, and the energization of the back-release-relay 35', over circuits that have been described. The back-release-relay 35', of course, energizes and in turn causes the energization of the release-magnet 37 of the first-selector B, which release-magnet now awaits the disengagement of the release-springs 203, 204 and 205 at the substation A in order to restore the selector B to normal position. The simultaneous grounding of the trunk conductors 62 and 63 again energizes the line relays 84 and 85 of the connector F, with the result that the switch-shaft of the connector F is released, the side switch is restored to normal position, and the back-release-relay 80 of the second-selector G is energized. These operations having already been described, and being well understood, it is not necessary to further describe them. As soon as the connector switch shaft returns to normal position the connection between the wipers 81, 82 and 83 and the trunk line that leads to the first-selector E and to the line of the subscriber D is broken; therefore, the energizing circuits for the bridge-cut-off-relay 180 and for the pole changing and circuit-controlling relays 107 and 106 are destroyed with the result that the first-selector E is restored to the control of the substation D, and the talking battery removed from the line of the called subscriber. All this occurs at the instant that the release-springs of the substation A come into contact; but as soon as the release-springs separate (after the switch-hook descends sufficiently) the switches are then fully restored to their normal position in the manner already fully described.

The back release is provided in this system to enable the called subscriber to destroy a connection that some other subscriber has made with his line in case the calling subscriber delays in restoring the switching apparatus. Were it not for such a provision the called subscriber might once in a while

be inconvenienced by not being able to make a call. The called subscriber, by hanging up his receiver 210 and by grounding his line conductors 177 and 178 simultaneously 5 from the substation ground G^1 , in the usual manner, and over circuits similar to those described in connection with substation A, deenergizes the circuit-controlling relay 106 by short-circuiting said relay between 10 grounds G^1 and G^2 . This short-circuit extends from ground G^1 through the springs 226 and 225 to the vertical line conductor 177, thence through the circuit-controlling relay 106, differential relay springs 215 and 216 to the side switch wiper 92 and to ground G^2 . As soon as the said relay 106 deenergizes, the springs 172 and 173 come into contact and close the energizing circuit 15 for the release-magnet 89. This release circuit, as already described, is closed at the point between the trunk release springs 208 and 209, since the line relays 84 and 85 are energized, because the pole changing relay 107 is still energized. Therefore, the connector-shaft and side switch are restored, at 20 which instant the bridge-cut-off-relay 180 of the first-selector E is restored, the energizing circuit through the pole changing relay 107 is broken at the instant that the rotary line 25 wiper 82 leaves its engaging contact, and the back-release-relay 80 of the second-selector G energizes in series with the release-magnet 89 and causes the release of the second-selector G in a well-known manner. Furthermore, the energizing circuit for the pole 30 changing relay 47 of the repeater C (Fig. 1) is destroyed as soon as the pole changing relay 107 at the connector F deenergizes. As soon as the pole changing relay 47 de- 35 energizes, the springs which it controls return to normal position, and as a result the flow of current through the transmitter 3 of the substation A is cut off and the line relays 44 and 45 regain their normal condition. The calling subscriber at substation A, 40 whenever he is ready, may eventually hang up his receiver, with the result that the selector B is released and the trunk conductors 62 and 63 are both grounded momentarily, as fully described in connection with the front release before the called subscriber answers. The simultaneous grounding of the trunk conductors 62 and 63 (since the switches at central #2 are already released) 45 does not disturb the apparatus at said office to carry it out of normal condition.

In the repeater the various coils may be of any suitable resistance, but it is found that good results are obtained if the coils 44 and 45 are each of one hundred and fifty ohms, while the resistance-coil 48 may have a resistance of sixty ohms; the windings of the differential relay 46 three hundred and fifty ohms each, and the pole changing relay 47 five hundred ohms.

From the foregoing it will be seen that the repeater is of such character that it serves to connect each side of a calling telephone line with the non-corresponding side of the called telephone line. In other words, the so-called vertical conductor of the calling line will be connected with the so-called rotary conductor of the called line, and the rotary conductor of the calling line will be connected with the vertical conductor of the 70 called line. With this arrangement the condenser in the vertical side of the trunk line circuit will not be subject to discharges as a result of impulses transmitted over the vertical side of the calling subscriber's line, and consequently the condensers thus employed will not tend to produce any confusion or uncertainty of action on the part of the second-selector, nor on the part of the connector. The apparatus will, of course, operate without having the repeater line conductors crossed, but with this crossed arrangement of the repeater line conductors, in combination with the common battery arrangement for supplying talking current over the 75 telephone lines to the subscribers' transmitters, I find that better results are obtained, and that the apparatus, particularly the second-selectors and the connectors, will in the long run operate with more certainty of 80 action. In other words, with this crossed arrangement of the line conductors, in combination with the common battery connections for talking purposes, much less delicate adjustment is necessary for the line relays, 85 particularly those of the selector and connector, in order to insure the proper operations. It will be understood, of course, that in any event the relays must all be properly adjusted, as by suitably tensioning 90 the springs of the relay armatures, so as to insure the desired operations; but as stated, and with my improved arrangement, a less delicate adjustment is possible, particularly 95 with respect to the line relays of the second-selectors and the connectors.

In the repeater I combine the crossed line conductors with line relays for supplying talking current to the calling telephone line, and with a trunk release circuit controlled 100 by said line relays; and in addition I preferably combine the crossed line conductors with a differential relay, whereby the trunk line circuit at one side of the cross therein is controlled by the normally closed contacts of the said differential relay. With this arrangement the switch operating impulses are efficiently and accurately repeated from one side to the other of a cross in the 105 trunk line, and at the same time the talking current from the common talking battery is effectively supplied to the circuit at each side of said cross, the repeater having the further function of closing a trunk release circuit back through the first-selector 110 115 120 125 130 135

or other suitable switch, in the direction of the calling subscriber. In this way three trunk conductors may be employed between the first-selector and the repeater, and between the second-selector and the connector, while only two crossed trunk conductors are employed between the repeater and the second-selector. As explained, the batteries which supply current for operating the selectors and connectors, or other suitable switching machines, as well as the repeaters, are also employed for supplying electrical current over the telephone lines to charge the microphone transmitters connecting the lines at the subscribers' substations. Preferably, for the purpose of trunking between two distant exchanges, one battery is employed for supplying current through the repeater to the calling telephone line, and another battery is then employed for supplying current through the connector to the called telephone line—that is to say, when the two lines are located at different exchanges. It will be understood, of course, that a subscriber of one exchange may call a subscriber of the same exchange without using a repeater, and by the use of three-conductor trunks throughout the connection between the calling and called lines. For trunking between exchanges, however, only two crossed conductors are employed for each trunk line.

In Fig. 3 it will be seen that the line conductors of the repeater are crossed in front of the condensers 49 and 50, rather than back of the condensers, which latter is the case in Fig. 1. In Fig. 3, however, the upper condenser 49 is connected temporarily, that is, during the establishment of a connection—of course, with the rotary side of the calling subscriber's telephone line, while the condenser 50 is connected also temporarily, of course, with the vertical side of the calling subscriber's line. With this arrangement the vertical trunk conductor 62 runs directly from the condenser 49, while the rotary trunk conductor 63 extends directly from the condenser 50, the cross in the circuit being located between the condensers and the bridge of the line relays 44 and 45. For the broader purposes of my invention the line conductors of the repeater may be crossed either in front or in rear of the condensers. With either arrangement any kick-through a condenser from the vertical side of the calling subscriber's line will be communicated to the rotary side of the trunk line, thus precluding any confusion or uncertainty in the action of the second-selector, or of the connector, as the case may be; and in a similar way any kick through a condenser from the rotary side of the calling subscriber's line will be communicated to the vertical side of the trunk line. At the same time an efficient

talking circuit is provided, the crossing of the line conductors at the repeater, having, of course, no detrimental effect on the voice currents. With either arrangement only two crossed trunk conductors are necessary between a repeater and the second-selector, and at the same time three-conductor trunks may be employed between the first-selector and the repeater, as well as between the second-selector and the connector.

What I claim as my invention is—

1. In a telephone exchange system, the combination of a line circuit having crossed conductors, a pair of line relays bridged across the circuit at one side of the cross therein, inductive connections in the circuit at the other side of said cross, an automatic switch in the circuit, means by which the calling subscriber uses said relays for controlling said switch, and means for supplying talking current through the windings of said relays to the calling end of said circuit.

2. In a telephone exchange system, the combination of a line circuit having crossed line conductors, an automatic switch connected in the circuit at one side of the cross therein, a pair of relays bridged across the circuit at the other side of said cross, means by which the calling subscriber employs said relays for controlling said automatic switch, and means for supplying talking current through the windings of said relays to the calling end of said circuit, and through the said automatic switch to the called end of said circuit.

3. In a telephone exchange system, the combination of a calling telephone line, a called telephone line, a trunk line connection temporarily connecting the two telephone lines together, said trunk line connection comprising a pair of crossed line conductors, whereby the so-called vertical conductor of one telephone line is connected with the so-called rotary conductor of the other telephone line, a connector-switch by which the trunk connection is established directly with the called telephone line, a pair of relays bridged across the trunk line connection at a point between the calling telephone line and the said crossed line conductors, a battery for supplying current through the windings of said relays to the calling telephone line for talking purposes, another battery for supplying current through the said connector-switch to the called telephone line for talking purposes, and means by which said relays are employed by a subscriber to control said connector for releasing purposes.

4. In a telephone exchange system, the combination of a connector, a pair of line relays for said connector, a pair of repeater relays, a pair of crossed line connectors between the repeater relays and the connector relays, a calling telephone line, a

- called telephone line, a battery for supplying talking current through the windings of the repeater relays to the calling telephone line, another battery for supplying talking current through the connector to the called telephone line, and means by which the calling subscriber employs said repeater relays for controlling the energizing of the connector relays.
- 19 5. In a telephone exchange system, the combination of a trunk line having its opposite sides crossed at a point between the ends thereof, a pair of differential relay windings bridged across the trunk line at one side 40 of the cross therein, a relay bridged across the trunk line at the other side of the said cross, the continuity of the last mentioned relay bridge being controlled by the said differential relay.
- 20 6. In a telephone exchange system, the combination of a trunk line having its opposite sides crossed at a point between the ends thereof, a pair of differential relay windings bridged across the trunk line at one side of the cross therein, a relay bridged across the trunk line at the other side of the said cross, the continuity of the last mentioned relay bridge being controlled by the said differential relay, and means for supplying talking current through the differential relay windings, together with a calling subscriber's microphone transmitter connected to receive said talking current.
7. In a telephone exchange system, the combination of a line circuit having crossed 45 conductors, a pair of line relays bridged across the circuit at one side of the cross therein, inductive connections in the circuit at the other side of said cross, an automatic switch in the circuit, said switch having one motion to select groups and another motion to connect with a line in any group selected by the first motion, means by which the calling subscriber uses said relays for controlling said switch, and means for supplying talking current through the windings of said 50 relays to the calling end of said circuit.
8. In a telephone exchange system, the combination of a line circuit having crossed line conductors, an automatic switch connected in the circuit at one side of the cross therein, said switch having one motion to select groups and another motion to connect with a line in any group selected by the first motion, a pair of relays bridged across the 55 circuit at the other side of said cross, means by which the calling subscriber employs said relays for controlling said automatic switch, and means for supplying talking current through the windings of said relays to the calling end of said circuit, and through the said automatic switch to the called end of said circuit.

Signed by me at Chicago, Cook county, Illinois, this 19th day of July, 1906.
